COMBINED TOOTH BRUSH, PASTE TUBE
HOLDER, AND SAVINGS BANK

Neil R. Renn and Madeline S. Renn, Progress, Pa.

Application April 30, 1958, Serial No. 50,670

Term of patent 14 years

(Cl. D4—3)

The paste tube and tooth brush depicted in broken lines are for illustrative purposes only.

We claim:

The ornamental design for a combined tooth brush, paste tube holder and savings bank, as shown and described.
